Primary Examiner — Patricia A Palasik

(74) Attorney, Agent, or Firm — BCF LLP

(57) **CLAIM**

The ornamental design for an industrial robot, as shown and described.

DESCRIPTION

1. Industrial robot
2. Industrial robot

Figure 1.1 is a perspective view of an industrial robot according to a first embodiment of the design;

Figure 1.2 is a top plan view thereof;

Figure 1.3 is a bottom plan view thereof;

Figures 1.4 and 1.5 are front and rear views thereof;

Figures 1.6 and 1.7 are left and right views thereof;

Figure 2.1 is a perspective of the industrial robot according to a second embodiment of the design;

Figure 2.2 is a top plan view thereof;

Figure 2.3 is a bottom plan view thereof;

Figures 2.4 and 2.5 are front and rear views thereof; and

Figures 2.6 and 2.7 are left and right views thereof.

(Continued)

Portions of the industrial robot illustrated by broken lines are not part of the claimed design.

1 Claim, 14 Drawing Sheets
